UNITED STATES PATENT OFFICE.

DOROTHY H. PULLEY, OF CHARLOTTE, NORTH CAROLINA.

DESIGN FOR A MOTOR METER.

Application filed April 5, 1927. Serial No. 21,459. Term of patent 14 years.

To all whom it may concern:

Be it known that I, DOROTHY H. PULLEY, a citizen of the United States, residing at Charlotte, in the county of Mecklenburg and State of North Carolina, have invented a new, original, and ornamental Design for a Motor Meter, of which the following is a specification, reference being had to the

accompanying drawing, forming part thereof.

The figure is a plan view of a motor meter, showing my new design.

I claim:

The ornamental design for a motor meter, as shown.

MRS. DOROTHY H. PULLEY.
